UNITED STATES PATENT OFFICE.

FRANK L. DARWIN, OF MARQUETTE, KANSAS, ASSIGNOR OF SEVEN-EIGHTHS TO HANS HANSON, JOHN J. MOTHANDER, ROBERT SOHLBERG, FREDERICK WEIHERMILLER, ALBRECHT HAERTLEIN, FRED BURNISON, JOHN BURNISON, OSCAR ROSS, CHARLEY LINDSTROM, S. C. BYBEE, AND GUSTOF WILLIAM HANSON, OF MARQUETTE, KANSAS, AND C. A. INGEMANSON.

RAILWAY-SWITCH.

SPECIFICATION forming part of Letters Patent No. 692,247, dated February 4, 1902.

Application filed May 14, 1901. Serial No. 60,181. (No model.)

To all whom it may concern:

Be it known that I, FRANK L. DARWIN, a citizen of the United States, residing at Marquette, in the county of McPherson and State 5 of Kansas, have invented certain new and useful Improvements in Railway-Switches; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in stub-shafts and switch-stands, and especially to the provision of means as a substitute for the ordinary frog for making a well-connected track-bearing in either position of the switch, and the various details of the invention, together with arrangement and combination of parts, will be hereinafter more fully described and then specifically defined in the appended claims.

25 The invention is clearly illustrated in the accompanying drawings, which, with the letters of reference marked thereon, form part of this application, and in which drawings—

Figure 1 is a top plan view of a switch, 30 showing switch-rails in place for the main-track use. Fig. 2 is a similar view showing the switch open or in position for siding purposes. Fig. 3 is a detail view of a bed-plate, on which a switch-point rests and swings. Fig. 3^a is an edge view of the plate shown in Fig. 3. Fig. 3^b is a detail view of one of the switch-points. Fig. 3^c is an edge view of the switch-point shown in Fig. 3^b. Fig. 4 is a vertical cross-section of the stub-rails, with the switch-stand 35 and connecting parts shown in elevation. Fig. 5 is a vertical sectional view of the mechanism for throwing simultaneously connected parts of the switch. Fig. 5^a is a sectional view horizontally through the mechanism 40 illustrated in Fig. 5. Fig. 6 is a plan view showing the arrangement of parts when thrown to form a crossover. Fig. 6^a is an ele-

vation of the construction shown in Fig. 6, a portion being shown in cross-section. Fig. 7 is a top plan view of the modified form of 50 crossover. Fig. 7^a is a vertical sectional view showing in elevation the parts illustrated in Fig. 7. Fig. 8 is a view showing in elevation the switch-stand, with parts shown in vertical section. Fig. 8^a is a similar view taken 55 at a slightly-different angle, parts being shown in section; and Fig. 9 is a sectional view horizontally through the switch-throwing rod.

Reference now being had to the details of the drawings by letter, A and A' designate the 60 rails of the main track, and B and B' the rails of the switch-tracks, which are diagonally disposed with reference to the main tracks, one of which, B', is disposed between the tracks A and A'. In the line of the main-track rails 65 are spiked two plates C and C', which are similar in construction and have respectively raised rail-like projections D and D', which are fastened in alignment with the rails A and A'. The other ends of the plates have 70 similar raised rail portions E and E' and F and F', respectively, which are in line with the main and side track rails. Between the raised rail projections E, F, and D at one end of the plate C is disposed a stub-rail G, while 75 between the raised rail projections F', E', and D' is a stub switch-rail G'. These stub switch-rails G and G' are held in parallel relation by means of the bridle-rods H, I, J, and K, which slide in grooves h, i, j, and k in 80 the plates C and C'. The bridle-rods are bolted fast, as at M, to the flanges L and L' on the stub switch-rails G and G'. Mounted on the plates H are the stops a and b, which serve to limit the throw of the switch-points 85 G and G' in one direction or the other as they are brought into contact with one edge or the other of the plates C and C'.

Referring to Fig. 4 of the drawings, means for locking the switch closed is illustrated, 90 comprising a spring-actuated bolt N, which passes through an aperture in the plate or rail C and its free end engaging in a recess in the under face of the stub switch-rail G.

This bolt is mounted in a yoke P, fastened to the bottom of said plate C, and a spring O, bearing between said yoke and a collar on the bolt N, serves to hold the latter normally in a locked position. Pivotaly connected to the lower end of said bolt is an angle-lever Q, which is pivoted to the stringer or tie R at its angled portion, said lever Q in turn being pivoted to the rod S, which is pivoted at one end of the angle-lever T, which is also pivoted at its angle portion to the tie R. One arm of said lever T is projected outward and forms a foot-tread, which when depressed will cause the spring-actuated bolt to be withdrawn from its engagement with the under surface of the stub switch-point G.

The switch-stand N is mounted upon the tie R and has secured thereto a casing V, which is fastened horizontally to the upper part of the stand, with its center projecting beyond the edge of the tie R, and is centrally apertured to receive the vertical switch-rod W. Keyed to said switch-rod is a hand operating-wheel Y, also a lever X, which is keyed to rotate with said rod. In the bifurcated end of said lever is pivoted an operating-handle Z, which is adapted to swing into one of the notches c or d in said casing when the switch is closed or open. This handle may be held clear of the casing by means of a spring-catch e, which is mounted on said hand-wheel Y and comprises two spring-arms, between which the handle is frictionally held above the casing when swung between said arms, in which position it will not interfere with the rotation of the switch-rod. This casing is made up of two plates, the bottom one of which contains the locking parts, suitably positioned therein, and a top plate or thin covering, incasing the locked parts. When the handle Z is turned down in the stub-notch C, which is the position in which the switch is closed, a hasp A², which is hinged to a pin on the circumference of the casing, is swung across said notch, confining said handle therein. This hasp has at its end a hook g, which is adapted to engage the spring-actuated bolt l, which is mounted in a block B², which is seated in said casing, said bolt being held at its farthest outward throw by means of a spring and in position to receive the catch z when the hasp is in the position illustrated in Fig. 9 of the drawings. This spring-actuated bolt may be withdrawn by means of a key of any suitable construction, which may be inserted in the casing for the purpose of engaging the projecting portion of the bolt, so as to withdraw it out of the path of the catch carried by the latch A². When the latch is released, a spring m, which is mounted within the casing, will throw the hasp outward, allowing the handle Z to be removed from the notch c.

To limit the throw of the lever X, projecting lugs p and p' are provided, against which the handle is adapted to strike to limit its movement in opposite directions, accordingly

as it is desired to throw the switch open or closed. The bottom plate of the casing is secured fast to the top of the stand U by four cap-screws n, n', n'', and n''', having sufficient space cored out to leave the heads below the cover-plate, which is in turn fastened to the bottom plate with four flat-head machine-screws o, o', o'', and o'''.

Secured to the switch-rod at any suitable location is an arm C², to the end of which is pivoted one end of the bar D², the other end of which bar is pivoted to the bar H. As the switch-rod is rocked or rotated the stub switch-rails G and G' may be thrown into the two different switch positions. The rod W passes through the bearing E², which is a part of the base-standard U, also through another bearing F², which is a part of the cover G² of the box H². Both these bearings have removable caps, and the cover G² has a flange q, (shown in Fig. 8 of the drawings,) which is bolted securely to the tie R, while the base I² of the box H² may be bolted or otherwise securely fastened to the cover G². The end of the rod W is mounted in a bearing in a boss r of the base I². Secured to the switch-rod W at a suitable location within the box H² and at right angles to the arm C² is an arm J², to the end of which is pivoted one end of the short bar K², the other end of which is pivoted to one end of the half-turnbuckle L², and the threaded end of the rod N² engages said turnbuckle and is held therein by means of a threaded nut M². The rod N² slides in a pipe O², which is fitted in the box H², thus keeping the mechanism completely housed from dirt and water. The opposite end of the pipe O² is fitted within a similarly-constructed box H³, in which the opposite end of the rod N² slides and which is threaded in one end of the half-turnbuckle L³ and clamped with nut M³, the other end of the turnbuckle L³ being pivoted to one end of the short bar K³, which in turn is pivoted to the end of the arm J³, secured to the vertically-secured stub-shaft W³. The lower end of the stub-shaft W³ is journaled in a bearing contained in the bottom part I³ of the box H³, the other end having a bearing in the plate P², which is secured to the top of the ties Q² and Q³. (Shown in Fig. 5 of the drawings.)

The stub-shaft W³ has secured to it at a suitable location at right angles to the arm J³ an arm C³, the end of which is pivoted in the bar D³, which in turn is pivoted to the flange of the short point R², Fig. 6 of the drawings, which point R² is pivoted to the siding-rail B', which has a space cut out for the rod D³ to work in, this plate being passed under the main rail A and spiked, with the rails, to the ties. The main rail A has a part of the ball Y², Fig. 6, cut away parallel to the side of the rail B' and wide enough to allow the flange of a wheel to pass through when the pointed rail R² is thrown against the main track at A. The adjacent rail of the siding on the outside

of the main track is pointed and bolted fast to the main rail A and held in proper angle by the block U², Fig. 6 of the drawings.

In Figs. 7 and 7^a I have shown a slight modification in the construction of the cross-over. It consists of the plate V², which has raised rail-like projections, which are parts of and are in line with their respective track and siding rails. The raised projection s is made up of the junction of the raised projection t, which is bolted with standard angle-bars to the main-track rail A, and the raised projection u, which is bolted to the adjacent rail B' of the siding outside of the main tracks. The projection t' is in line with the projection t and is bolted to the main-track rail A, and the raised projection u', which is in line with the raised projection u, is bolted to the end of the part of the siding-rail B' lying diagonally between the main-track rails. At the concaved end of the projection s is pivoted a piece X², which has a lug projecting down through an aperture in the shouldered end of the projection s and held thereto by means of a key y. Lugs v and v' are provided to limit the outward throw of the point X² in opposite directions, accordingly as the switch is open or closed, and a spring x, which is carried by a lug w on the plate V², tends normally to hold the point X² in alignment with the main-track rails.

Having thus described my invention, what I claim to be new, and desire to secure by Letters Patent, is—

1. A switch mechanism, comprising the main and siding tracks, plates and stub switch-points mounted on the latter, bars connecting said points, stops mounted on one of said bars and adapted to limit the throw of said switch-points, combined with a switch-stand, a vertically-mounted rotatable switch-rod, pivotal link-and-lever connections between said rod and the bar carrying said stops, a spring-actuated bolt engaging one of said switch-points, and a foot-lever and connections with said bolt, as set forth.

2. A switch mechanism, comprising in combination with the main and side tracks, switch-points connecting the same, mounted as described, stops for limiting the throw of said points, vertically and rotatably mounted switch-rod, pivotal link connections between said switch-rod and said switch-points, hand-wheel keyed to rotate with said switch-rod, a casing and switch-stand on which the same is mounted, a lever having a pivoted handle at its end, adapted to be held in notches in said casing and locked therein, and means for holding said handle out of engagement with the casing when the switch is open, as set forth.

3. A switch mechanism, comprising in combination with the main and side rails, the switch-points connected together as described, the stops for limiting the throw of said points,

switch-stand, the switch-rod vertically mounted in suitable bearings and having pivotal link connections with said switch-points, the hand-wheel keyed on said switch-rod, a casing mounted on said switch-stand, a lever keyed to the switch-rod and having a pivoted handle secured to its end, adapted to be locked within said casing when the switch is closed, and a spring-clasp carried by the hand-wheel and adapted to hold said handle out of engagement with said casing when the switch is open.

4. A switch mechanism, comprising in combination with the main and siding tracks, the switch-points, the switch-stand, pivotal link connections with said points, and stops to limit the throw of the points, a hand-wheel keyed to the switch-rod and a lever also pivoted to said rod, a handle pivoted to the end of said lever, a casing having notches in its circumference and stops to limit the throw of said lever, a spring-actuated hasp pivoted adjacent to the circumference of said casing, a spring-actuated bolt mounted within the casing, adapted to receive and lock said hasp across the entrance to the notch in which the pivoted handle is seated when the switch is closed, and means for releasing said hasp, as set forth.

5. In combination with the main and side tracks, switch-points, switch-stands, pivotal link connections between said points and the switch-rod, the casing secured to said stand, hand-wheel and lever keyed to the switch-stand, a spring-catch secured to the under side of said hand-wheel, a handle pivoted to the bifurcated end of said lever, adapted to engage in notches in the circumference of the casing, stops on said lever, a hasp, spring-actuated, and pivoted near the circumference of the casing, a hook at one end of said hasp, a block seated within said casing, and a spring-actuated bolt carried by said block, the outer end of said spring-actuated bolt disposed in the path of said hook, and means for releasing said hook to allow the spring-actuated hasp to open to release the pivoted handle, which may be held in one of said notches, as set forth.

6. In combination with the switch-points, means for throwing the same, the apertured plate C, a bolt N passing through said plate and engaging a recess in the switch-point, the yoke secured to the under face of said plate, a spring interposed between said yoke and a collar on the bolt, the foot-lever and link-and-lever connections between same and said bolt, as set forth.

In testimony whereof I hereunto affix my signature in presence of two witnesses.

FRANK L. DARWIN.
